UNITED STATES PATENT OFFICE.

HENRY A. HUGHES, OF RIO GRANDE, NEW JERSEY.

DIFFUSION APPARATUS FOR THE EXTRACTION OF SUGAR FROM SORGHUM.

SPECIFICATION forming part of Letters Patent No. 395,145, dated December 25, 1888.

Application filed December 27, 1887. Serial No. 258,967. (No model.)

To all whom it may concern:

Be it known that I, HENRY A. HUGHES, of Rio Grande, Cape May county, New Jersey, have invented a new and useful Improvement 5 in Diffusion Apparatus for the Extraction of Sugar from Sorghum, of which the following is a specification.

My invention relates to a new apparatus for extracting sugar from sorghum-cane by diffusion; and it consists in the construction and arrangement of said apparatus, substantially as hereinafter set forth.

My said apparatus, briefly described, consists of a series of cells or vessels, which are heated, preferably, by means of a steam or hot-water jacket surrounding all of said cells. In these cells is placed water. The cane, being previously disintegrated or shredded, is packed in perforated metal baskets, and these baskets are successively immersed in each of the cells in turn, so that the water in each cell is rendered constantly richer in sugar until a given density is attained and the cane is gradually depleted of sugar as it is transferred from cell to cell of the series. Mechanism is provided for lifting the cane-baskets into and out of the cells and from cell to cell, and suitable pipes and stock-cocks allow of drawing off the water from the cells at will.

In the accompanying drawings, Figure 1 is a view showing the battery of diffusion-cells in plan view and other portions of the apparatus in horizontal section on the line X X of Fig. 3. Fig. 2 is a plan view of a portion of the diffusion-cells on a larger scale than the same are shown in Fig. 1. Fig. 3 is a vertical section of the apparatus on the line Y Y of Fig. 1. Fig. 4 is a vertical section in detail of one of the diffusion-cells and adjacent parts of the apparatus with the cane-basket in the cell. Fig. 5 is a vertical section of one of the diffusion-cells with the cane-basket removed, showing also the receiving-trough connections for the liquid after diffusion is completed.

Similar letters of reference indicate like parts.

A is a vertical shaft, which at its lower extremity may form or be secured to the plunger 50 of the cylinder B. The upper portion of said shaft passes through a sleeve or bearing, C, in which bearing the shaft has free vertical

motion. The shaft is also free to rotate on its own axis in bearing C and cylinder B. Communicating with cylinder B beneath the shaft is a pipe, D, conducting water from a pump, as E. When water is forced into cylinder B, the shaft is raised upward by hydraulic pressure assisted by the counter-weight F, which is connected to the upper 60 end of shaft A by a cord or chain passing over the fixed pulleys G. When water is allowed to escape from cylinder B, as by pipe D', after the shaft A has been elevated, as aforesaid, said shaft then descends by its own 65 gravity.

Supported upon shaft A is a metal skeleton frame-work, H, consisting of radial members I, connected by vertical members J and horizontal circumferential members (not shown) 70 at the extremities of said radial members and by suitably-disposed diagonal members L, the whole producing a light but strong polygonal or circular structure.

Upon the flooring directly beneath the circumference of the frame-work H is a diffusion-battery. This consists of an annular tank, M. The bottom N, Fig. 5, of this tank is elevated, so that an air-space is left between said bottom and the floor. The top of 80 the tank M is covered by an annular plate, P, in which are circular apertures to receive the diffusion-cells 1 to 10. The top edges of tank M are flanged, and the covering-plate P is riveted steam and water tight to said flanges. 85 The upper edges of the cells 1 to 10 are also flanged and are riveted steam and water tight to the plate P. The tank M therefore forms a jacket which incloses all the cells 1 to 10. Into this jacket steam or hot water 90 may be admitted by the pipe Q, in order to heat the contents of the cells, and conducted from said jacket by the pipe R. The position and arrangement of pipes Q and R are not material, so long as they properly provide 95 for admission and escape of steam or hot water into and from the tank or jacket M.

The cells 1 to 10 are preferably made of sheet-copper and with convex bottoms to facilitate withdrawal of their contents. With 100 each cell is connected a short pipe-section, S, which extends through the inner wall of tank or jacket M and has a stop-cock, T. The delivery-orifices of the several draw-off pipes S are

disposed above an annular trough, U, which surrounds an opening in the floor upon which the diffusion-battery rests, through which opening the shaft A passes. The cylinder B 5 is supported upon a platform, V, directly below this opening. A workman standing on the platform V may conveniently manipulate all the stop-cocks T, and so cause any cell at will to discharge its contents into the circular 10 trough U. From trough U a pipe, W, conveys the sugar liquor to an evaporator, (not here shown,) whence, after evaporation, the material is conducted to such other apparatus as may be requisite for the obtaining of 15 sugar in crystallized form.

Returning now to the frame-work H, upon the outer periphery of this structure are disposed as many swinging brackets or cranes *a* as there are cells 1 to 10. Each bracket consists of a vertical pivot-arm, *b*, and an outwardly-inclined arm, *c*, and at the end of each arm *c* a hook is provided. The pivot-arms *b* are supported and turn freely in bearings *d* upon the frame H. The distance between 25 successive pivot-arms *b* equals the distance between the centers of successive cells 1 to 10, and the horizontal distance from the end of arm *c* to a point below pivot-arm *b* also equals the distance between centers of successive 30 cells. Hence, for example, as shown on the left of Fig. 1 by dotted lines, the arm *c*, having its pivot-arm *b* directly over the center of cell 10, may be swung inwardly, so as to bring whatever is carried on the hook at the end of 35 arm *c* directly over the adjacent cell, 1, and so for all other arms *c* and cells of the series.

At *e*, Fig. 4, is shown a receptacle for the cut cane, which I term herein a "cane-basket." It is made, preferably, of perforated 40 sheet-copper, and is provided with a cover, *f*, of the same material, which may be secured in place by any suitable means, as by a bar, *f'*, entering loops *f''* on the edges of the basket. A metal bail, *g*, serves to suspend the 45 cane-basket from the hooks of arms *c*.

Having described the construction of my apparatus, I will now set forth my process of diffusion.

The sorghum-stalks are cut up in short 50 lengths, freed from leaves, sheaths, and seed-heads, and then shredded. These various operations may be accomplished in any suitable way; but I prefer to perform them by the agency of certain apparatus invented by myself, not here shown and not necessary here to describe. I begin by filling the cells 1 to 55 10 with water and heating the same to 100° Fahrenheit or over by means of steam or hot water admitted into the tank or jacket M. A 60 cane-basket, which for present convenience I will designate as "basket 1," is now filled with shredded cane. The shaft A being in its lowest position—that is, the water being out of cylinder B—the swinging bracket-arm 65 *c* over cell 2, for example, is swung outward, and the basket 1 is suspended by the bail from the hook on said arm. Water is now

pumped into cylinder B, and shaft A is elevated sufficiently to allow the bottom of the suspended basket to clear the top of the tank 70 M. Then the arm *c* is swung inward so as to bring basket 1 directly over cell 1. (Dotted lines, Fig. 3.) Water is now allowed to escape from cylinder B, the shaft A descends, and basket 1 is thus deposited in the water 75 in the cell 1. The hot water then acts upon the shredded cane to dissolve out a portion of the contained sugar. Another basket (which I will call "basket 2") is now filled with shredded cane and brought to the battery. 80 During the filling of the second basket or during any predetermined period of time basket 1 is allowed to remain in cell 1. When basket 2 is ready or when the predetermined interval of time has elapsed, basket 2 is attached to the bracket-arm which has its pivot 85 *b* above cell 1—that is, to the arm which, if all parts remained in their present position, and assuming the operation already described repeated, would result in placing basket 2 in 90 cell 10; but this last is not done. Basket 2 being attached to the arm above mentioned, shaft A is elevated, and of course basket 1 is lifted out of cell 1. Now shaft A is rotated on its own axis in the direction of the large 95 arrow, Fig. 1, so as to bring basket 1 over cell 2 next in succession on the right and basket 2 over cell 1 when its supporting-arm is swung inward. Shaft A is then lowered with this result, namely: Basket 2, containing fresh 100 cane, has been placed in cell 1, the water of which has already taken sugar from the contents of basket 1. Basket 1 has been shifted into fresh water in cell 2, which acts upon the now partially-spent cane there- 105 in. The same predetermined interval of time is now allowed to elapse and a third filled basket (basket No. 3) is prepared. This is hooked upon the bracket which has its pivot over cell 9, and which would (if the 110 shaft A were not again rotated) land this basket in cell 10; but the shaft is again raised and again rotated. The consequence is that basket 1, which has now been in cells 1 and 2, is placed in cell 3, basket 2 in cell 1 is 115 placed in cell 2, and basket 3, containing fresh cane, is placed in cell 1. Other baskets are successively got ready and the same operation repeated until finally every cell has a basket in it. This naturally will come to pass 120 when basket 1 has been successively in each and all of the cells and when ten baskets have successively been immersed in cell 1. Basket 1 will therefore have been subjected to ten washings, each washing in turn being with 125 fresh water and each body of water extracting a portion of the sugar which remains in the cane after the preceding washing. On the other hand, ten baskets have in turn been immersed in cell 1. From the cane in each 130 basket successively the water in cell 1 has dissolved sugar. Consequently the density of the sugar-liquor in cell 1 becomes greater and greater with each successive basket, and

finally, after the tenth basket has been received, the liquor in said cell may be dense enough or sufficiently charged with sugar to be ready for evaporation. This being the 5 case, the stop-cock T in the tube S, connecting with cell 1, is opened, and the contents of that cell are allowed to escape into trough U, and so to pass to the evaporator or wherever else desired. Cell 1 is then cleansed from 10 sediment and refilled with fresh water, and the contents of basket 1 now exhausted are thrown out and fresh cane put in. The re-filled basket is, however, not placed in the fresh water of cell 1, but in the liquor of cell 15 2, because, although cell 1 before emptying had received ten baskets in turn, cell 2, obviously, had received but nine. Consequently the tenth immersion in cell 2 is made with the eleventh basket.

20 While the operation above described is a continuous one in the sense already explained, each vessel in the series being discharged in turn and each in turn refilled with fresh water, it should be understood that I 25 do not limit my invention to such a continuous process. It is quite practicable, for example, to fill ten baskets with cane and place all at once in the ten cells. Then after a given time the baskets may be raised from 30 the cells and the shaft A rotated, so as to allow basket 1 to be placed in cell 2, basket 2 in cell 3, and so on around the circle, and this may be repeated until each basket has been in each cell. Then assuming all the 35 liquor in all the cells thus to be brought at the same time to the desired density, all stop-cocks may be opened, so draining all the cells at once. This mode of operation is, however, less preferable in point of economy and 40 expedient to the continuous process already described.

In another application for Letters Patent simultaneously filed herewith, Serial No. 258,966, I have fully described and claimed 45 my aforesaid process. The subject-matter of said application is therefore herein disclaimed.

I claim—

1. The combination of a series of independent cells or tanks with a steam or water jacket wherein said cells are set, a discharge-duct connecting with each cell and extending through said jacket, and a trough into which all of said ducts enter and deliver the 55 contents of said cells, substantially as described.

2. The combination of a series of cells or water-vessels with a means (such as a steam or hot-water jacket) for heating said cells, a 60 series of pivoted crane-arms, and a support for said arms above said cells, each of said arms being pivoted in said support directly

above a cell and the length of each arm being such that when said arm is swung on its pivot its outer extremity may extend over 65 the next adjacent cell, substantially as described.

3. The combination of a series of cells or water-vessels with a means (such as a steam or hot-water jacket) for heating said cells, a 70 series of pivoted crane-arms, and a vertically-movable support for said arms above said cells, each of said arms being pivoted in said support directly above a cell, and the length of each arm being such that when said arm 75 is swung on its pivot its outer extremity may extend over the next adjacent cell, substantially as described.

4. The combination of a series of cells or water-vessels with a means (such as a steam 80 or hot-water jacket) for heating said cells, a series of pivoted crane-arms, and a horizontally-movable support for said arms above said cells, each of said arms being pivoted in said support directly above a cell, and the 85 length of each arm being such that when said arm is swung on its pivot its outer extremity may extend over the next adjacent cell, substantially as described.

5. The combination of a series of cells or 90 water-vessels with a means (such as a steam or hot-water jacket) for heating said cells, a series of pivoted crane-arms, and a vertically and horizontally movable support for said arms above said cells, each of said arms be- 95 ing pivoted in said support directly above a cell, and the length of each arm being such that when said arm is swung on its pivot its outer extremity may extend over the next adjacent cell, substantially as described. 100

6. The combination of the annular tank M with cells 1 2 3, &c., therein, vertically-movable rotary shaft A, support H, and swinging arms a, substantially as described.

7. The combination of the annular tank M 105 with cells 1 2 3, &c., therein, rotary shaft A, hydraulic cylinder B, receiving the lower end of said shaft, support H, and swinging arms a, substantially as described.

8. The combination of the annular tank M 110 with cells 1 2 3, &c., therein, delivery-pipes S, trough U, vertically-movable rotary shaft A, support H, and swinging arms a, substantially as described.

9. The combination of the annular tank M 115 with cells 1 2 3, &c., therein, vertically-movable rotary shaft A, frame-work H, and arms a, having their vertical portions b pivoted in the periphery of said frame-work, substantially as described.

HENRY A. HUGHES.
